UNITED STATES PATENT OFFICE.

CHARLES J. TÓTH, OF STAPLETON, NEW YORK, ASSIGNOR TO INTERNATIONAL PROCESS AND ENGINEERING CORPORATION, OF NEW YORK, N. Y., A CORPORATION OF NEW YORK.

INTERNAL-COMBUSTION ENGINE.

Application filed April 29, 1922. Serial No. 557,431.

To all whom it may concern:

Be it known that I, CHARLES J. TÓTH, a citizen of the Republic of Uruguay, and resident of Stapleton, New York city, county 5 of Richmond, and State of New York, have invented certain new and useful Improvements in Internal-Combustion Engines, of which the following is a specification.

The invention relates to internal combustion engines, and particularly to such engines of the two cycle type. One of the objects of the invention is the provision of an improved engine of this type having its parts so constructed and related as to provide for "supercharging" the cylinder. In the present construction the exhaust ports of the cylinder are closed, cyclically, before the inlet ports are closed. The air or mixture thus continues to pass through the inlet ports into the cylinder during the interval between the closing of the exhaust ports and the closing of the inlet ports, and this continued charging of the cylinder after the exhaust ports have closed is what is referred 20 to herein as the "supercharging" of the cylinder. In the usual form of two-cycle engines such action is not possible, because of the fact that in them the exhaust ports remain open until after the inlet ports have 25 closed, so that no air or mixture can be forced into the cylinder after the exhaust openings thereof have been closed, except by arrangements employing a valve as in a Diesel type of engine, which valve is eliminated in the present invention.

In attaining this supercharge a precompression chamber may be provided, in which chamber air or hydrocarbon fuel mixture, as the case may be, is compressed and then 30 discharged into the combustion chamber through suitable ports.

In the embodiment of the invention herein shown and described, this supercharge is accomplished by providing two pistons 45 operating in the cylinder, one being given a lead over the other, the first controlling the exhaust ports while the second controls the inlet ports; the arrangement and construction of the ports and the relative relation of the pistons being such that the exhaust ports are closed before the inlet ports are closed, and such that the exhaust ports are opened before the inlet ports are opened.

55 In the present invention the lead is ob-

tained as follows. A pair of pistons in an engine unit are connected by rods to a revolving crank or cranks; on the crank or cranks, interposed between the same and the surrounding portions of the connecting rods, eccentrically mounted bushing portions or bushings are arranged, and caused to rotate about the crank or cranks during the rotation of the latter. The bushing portions or bushings are so arranged and rotated as to give one piston the desired lead over the other at suitable times.

In one form of the invention a duplex cylinder is used having parallel cylinder portions, in which operate pistons connected by connecting rods of equal length to the same throw of the crank shaft. The latter has an eccentrically mounted sleeve or bushing thereon, which itself rotates about the crank pin during the rotation of the latter through its stroke circle. One part of this bushing, to which one of the connecting rods is connected is so arranged that its eccentric position is in advance, angularly, with respect to the eccentric position of the other bushing portion, to which the other connecting rod is connected.

The result of such a construction, in the present invention, is to cause one piston to reach certain points in its stroke before the other piston reaches corresponding points. Various advantages, in addition to those referred to above, may be obtained by such an arrangement. Thus, the exhaust ports may be caused to open fully, more speedily than is usual, while the full opening of the inlet ports may be somewhat retarded, in comparison with the known constructions. By opening the exhaust ports fully, during the early part of the period during which these ports are at least partly open, the exhaust of burnt gases may be quickly accomplished. Also, a greater vacuum than is usual will be formed in the cylinder during the period when, as stated above, the exhaust ports are open before the inlet ports are opened. This greater vacuum will be caused by the fact that the exhaust gases achieve a greater velocity than is usual during the early part of the exhaust port opening period, because of the early full opening of the exhaust ports.

By not opening the inlet ports fully until the latter part of the period during which these ports are at least partly open, scaveng-

ing of the burnt gases from the cylinder will be accomplished by the action of less than the full amount of fresh charge. Accordingly there will be less likelihood of 5 a portion of fresh charge going out of the exhaust ports with the burnt gases. Preferably, the maximum opening of the inlet ports occurs only at about the time the closing of the exhaust ports is completed.

10 Other objects of the invention relate to the provision of improved features of construction and combinations of parts as will be more fully set forth hereinafter.

In order that a clearer understanding of 15 the invention may be had attention is hereby directed to the accompanying drawings illustrating certain embodiments of the invention.

In the drawings—

20 Fig. 1 represents a vertical section taken through an engine unit embodying the invention, this unit comprising a duplex cylinder having parallel cylinder portions side by side;

25 Fig. 2 is a diagram illustrating the operation of the engine;

Figures 3 and 4 are horizontal sections taken respectively on line 3—3 and line 4—4 of Fig. 1, the pistons being omitted;

30 Figures 5 and 6 are vertical sections taken respectively on lines 5—5 and 6—6 of Fig. 1;

Fig. 7 represents a longitudinal section taken through an engine unit comprising a modified form of the invention, this unit 35 comprising a cylinder having pistons mounted in the opposite end portions thereof to move towards and away from each other;

Figures 8, 9 and 10 are sections taken respectively on lines 8—8, 9—9, and 10—10 of 40 Fig. 7;

Fig. 11 is a diagrammatic side elevation of a multiple cylinder engine formed of units similar to those shown in Fig. 1;

Fig. 12 is a diagrammatic top plan view 45 of a multi-cylinder engine made up of units similar to the one shown in Fig. 7, in one arrangement of the same; and

Fig. 13 is a diagrammatic top plan view 50 of a multiple cylinder engine composed of units similar to that shown in Fig. 7, with a different arrangement of the units from that shown in Fig. 12.

Referring to the drawings and particularly to Fig. 1, an internal combustion engine is illustrated having a duplex cylinder 55 which may comprise a casting 1 mounted above the crank case 2. The cylinder is provided with two parallel downwardly extending cylinder portions 3 and 4 arranged side by side with a common combustion chamber 5 above the same. The crank shaft 6 is mounted in suitable bearings in the crank case and is provided with a single crank or throw 7. Pistons 8 and 9 are mounted for 60 reciprocation in the two parallel cylinder

portions 3 and 4, and are connected by connecting rods 10 and 11 to crank 7, an eccentric sleeve or bushing being mounted on crank 7 and, therefore, interposed between the crank and the lower portions of the connecting rods surrounding the same. Connecting rods 10 and 11 are of equal length. The eccentric bushing referred to will presently be described.

It will be noted that the parallel cylinder 75 portions 3 and 4 are arranged, in the construction shown in Figs. 1, 3 and 4, with their axes in a plane in which the axis of crank shaft 6 is also included. Cylinder portion 3 is provided with the exhaust port 80 openings 13 extending therethrough, these ports being controlled by piston 8. Cylinder portion 4 is provided with the inlet ports 14 extending therethrough, these ports being controlled by piston 9. Cylinder portion 3 85

has an outer wall 3¹ spaced from the inner wall within which piston 8 operates and cylinder portion 4 has an outer wall 4¹ spaced from the inner wall within which piston 9 operates. Ports 13 and 14 extend 90

through the inner walls of the cylinder (Figs. 1 and 3). An annular space 13^a is provided between the inner and outer walls of cylinder 3, to partly surround the inner wall, and exhaust outlet 13¹ in the outer wall 95

3¹ connects this space with the outside air or with an exhaust muffler. A division wall 25 is provided between the two parallel cylinder portions 3 and 4, this wall extending upwardly into the upper portion of the 100 interior space of the cylinder, with an open space above the same, as shown in Fig. 1.

Further description of the cylinder construction and of the pistons 8 and 9 will be given hereinafter. It is thought that the 105 construction and operation of the device will be more clearly understood by giving at this point a description of the mechanism by which the pistons are reciprocated.

In the construction shown in Figs. 1, 5 and 6, a bushing indicated generally by the reference character 29 is mounted upon the crank 7, extending between crank discs 7¹, 7¹, of the crank shaft 6. Bushing 29 is mounted eccentrically upon the crank pin, a bearing sleeve 29^a preferably being interposed between the crank pin and bushing. The crank pin may conveniently be formed integral with one of the crank discs 110 7¹, with its other end secured to the other crank disc 7¹, or it may, of course, be formed entirely separate from both crank discs and secured thereto so that in either case the bushing 29 may be positioned thereon. In

115 the construction shown in Fig. 1 of the drawings, the crank pin is integral with the crank disc 7¹ at the left and extends through a suitable opening in the crank disc 7¹ at the right. The crank pin is shown as provided 120 with a screw-threaded portion 7^a of reduced

125 130

diameter at its right hand end upon which a nut 7^b is mounted, this nut being seated in a suitable counter-sunk opening in the right hand crank disc 7¹.

- 5 The bushing 29, as is shown in Figs. 1, 5 and 6, of the drawings, may conveniently be formed as one integral member having a portion 29¹ upon which connecting rod 10 is mounted, and a portion 29² upon which connecting rod 11 is mounted. A spur gear 30 is also integral with or secured to bushing 29 and concentric with crank 7, this gear engaging with an internal gear 31 which is fixedly mounted in the crank case 2.
- 10 The bushing portions 29¹ and 29² each have the same amount of eccentricity, the axis of the portion 29¹ of the bushing being, however, advanced a certain number of degrees in the direction of rotation of crank 7, in relation to the axis of bushing portion 29². This will be evident from Figs. 5 and 6 in which the crank 7 is represented as being at its upper dead center, the rotation of the crank shaft being considered as in a counter-clockwise direction, as is shown by the arrows. It will be noted that the axis of bushing portion 29¹, indicated at 29^c, is located in an angular position a number of degrees in advance of the vertical plane extending through the center of the crank pin, while, as is shown in Fig. 6, the axis 29^d of bushing portion 29² is located an equal number of degrees to the rear of the same vertical plane. In order to facilitate reading the drawings the bushing portion 29¹ is indicated by A in Figs. 1 and 5 respectively, and the bushing portion 29² is indicated by reference character B in Figs. 1 and 6 respectively.
- 15 In the construction shown in Fig. 1 the spur gear 30 is positioned between the bushing portions 29¹ and 29², at about the intermediate point in the length of the bushing. The spur gear is coaxial with crank pin 7 while the internal gear 31 is coaxial with crank shaft 6. In the construction shown the spur gear has one-half as many teeth as the internal gear, so that the gear ratio between the spur gear and the internal gear will be two to one.

20 With such a construction spur gear 30 will constantly mesh with internal gear 31 during the rotation of the crank shaft, the spur gear and bushing 29 accordingly rotating about crank pin 7 with twice the angular speed of the crank pin; that is to say, the spur gear and bushing will make two complete revolutions about the crank pin during each revolution of the crank pin about its own center of rotation. The result of this arrangement, bushing portion 29¹ being advanced in its eccentricity in relation to bushing portion 29², will be to cause the connecting rods 10 and 11 to descend and ascend with variable speeds, pis-

ton 8 having a lead over piston 9 so as to open the exhaust ports 13 before piston 9 opens the inlet ports 14 and to close the exhaust ports 13 before piston 9 closes the inlet ports 14. This will be explained more fully hereinafter with reference to the diagram shown in Fig. 2.

I will now return to the description of the cylinder construction and of the two pistons 8 and 9. The piston 9, controlling the inlet ports 14, is provided with an inner hollow cylindrical portion 15¹, a top portion 16¹ and an outer concentric cylindrical portion 17¹. The piston 8 is similarly provided with portions 15, 16 and 17. This construction provides what I term a differential piston in each of the cylinder portions 3 and 4. A member 18, preferably a casting, is provided at the bottom of the two parallel cylinder portions 3 and 4, this member having cylindrical guide portions 20, 20¹, which constitute guides for the inner cylindrical piston portions 15 and 15¹. Member 18 is also provided with horizontal flanges or diaphragm portions 21, which serve to separate the interior of the crank case from a precompression chamber 27 provided above flanges 21 and hereinafter to be described.

The engine may be adapted to operate on a combustible mixture in which case the combustion chamber 5 will be provided with the usual spark plugs, or air alone may be drawn into the engine through the inlet ports and compressed to a considerable degree in the combustion chamber, in which case fuel will be injected into the combustion chamber through fuel injectors, at suitable times, as is the practice in the Diesel type of engine. I have illustrated the cylinder head 22 as provided with opening 23 in which a spark plug or fuel injector may be positioned. The upper portion of the cylinder may be suitably water jacketed, as is indicated at 24. The division wall 25 between the two parallel cylinder portions 3 and 4 extends upwardly into the upper portion of the interior space of the cylinder, as has been previously stated, and has a passageway indicated at 25¹ beneath the same for a purpose hereinafter to be described.

25 Exhaust ports 13 are controlled by the portions 17 of greatest diameter of piston 8 while the inlet ports 14 in the cylinder portion 4 are controlled by the portion 17¹ of greatest diameter of piston 9.

30 Ports 26 and 26¹, in cylinder portions 3 and 4 respectively (see Fig. 4) serve as inlet ports for the precompression chamber 27, and are also controlled by portions 17, 17¹, of greatest diameter of pistons 8 and 9. The precompression chamber 27 extends around cylinder portions 3 and 4, in the space above the horizontal flange 21 of member 18, within the outer walls 3¹ and 4¹, and around the

annular upwardly extending flanges 20, 20¹, of member 18. An intake opening 28 (Fig. 4) leads through the outer wall of the cylinder intermediate the outer wall portions 5 3¹ and 4¹, this opening leading into the annular space 28¹ which extends around the greater part of cylinder portion 3 between the inner and outer walls thereof and partly around cylinder portions 4 between the inner and outer walls thereof, as is shown in Fig. 4. The ports 26 and 26¹ are covered by the aprons or outer portions 17, 17¹, of pistons 8 and 9, until on the up stroke of the pistons, the outer aprons 17, 17¹, of the pistons begin to move past these ports. When the lower edges of the outer aprons 17, 17¹, of the pistons uncover ports 26 and 26¹ air or mixture, entering through opening 28 in the outer wall of the cylinder will be free to 10 flow in through ports 26 and 26¹ to occupy the unobstructed space above flanges 21, between the outer walls 3¹ and 4¹ and the inner cylindrical portions of the pistons. That is to say, the precompression chamber 15 will comprise the space between inner and outer walls 3 and 3¹, 4 and 4¹, the space below aprons 17, 17¹, and the bottoms of inner walls 3 and 4, and the annular spaces between apron 17, 17¹, and annular guides 20 20¹, and between aprons 17, 17¹ and the inner cylindrical portions of the pistons above guides 20, 20¹ when the pistons are raised into the position shown in Fig. 1. The precompression chamber portions extending about cylinder portions 3 and 4 are 25 connected together by the passageway 25¹ below the division wall 25, previously referred to.

The inlet ports 26, as shown in Fig. 4, may 30 and preferably are positioned at intervals around the circumference of cylinder portion 3. The ports 26¹ in cylinder portion 4, however, may be positioned around only a portion of the circumference of cylinder portion 4, so that room may be left for free communication between precompression chamber 27 and the inlet ports 14 which lead from the precompression chamber into the upper portion of the cylinder. This communication is established when ports 14 are 35 uncovered by the apron 17¹ of piston 9, by way of the upwardly extending portion 27¹ of the chamber 27 which extends upwardly, at the right hand side of cylinder portion 4, to the level of ports 14, as is shown in Figs. 1 and 4.

The air or mixture drawn into the precompression chamber on the up strokes of the pistons, as stated, will be compressed there- 40 in by the succeeding downward movement of the pistons, after the lower edges of the apron 17, 17¹, have passed over and closed ports 26, and 26¹. Opening 28 will connect with the outside atmosphere when the engine is to be provided with fuel injectors and

will be connected to suitable carbureting means when the engine is to be provided with spark plugs and is to operate on the usual atomized mixture or air and fuel. It has not been deemed necessary to illustrate any connection from opening 28 to a carburettor or the like, since, as stated, the invention is applicable to both forms of engine.

The operation of the engine may briefly be described as follows. On the upstroke of the pistons, air or mixture, as stated, will be drawn into the precompression chamber when ports 26 and 26¹ are uncovered towards the upper limit of movement of the pistons. In Fig. 1 the pistons are shown at or about their upper positions in which the inlet ports for the precompression chamber will be thus opened. When the pistons again descend this air or mixture will be compressed within chamber 27 until piston 9 has nearly reached its lowest position on the down stroke, when ports 14 will be opened by the upper edge of piston 9 descending past the same whereupon the compressed air or mixture in chamber 27 will pass through these ports into the combustion chamber above the piston.

Towards the end of the down stroke of the pistons, that is the working or power stroke of the pistons, the exhaust ports 13 will be opened, shortly before the inlet ports 14 are opened, because of the fact that piston 8 has a lead over piston 9, as stated. There will, accordingly, be a scavenging action of the cylinder while both exhaust and inlet ports are open and until the exhaust ports 13 are again closed on the next up stroke of the pistons. The lead of piston 8 on the down stroke is established because of the arrangement and operation of the eccentric bushing 29 on crank pin 7, as will shortly be more fully explained.

Piston 8 also establishes a lead on the up stroke, so that exhaust ports 13 will be closed before the inlet ports 14 are closed. A period of super-charging then follows, the precompressed air or mixture in chamber 27 continuing to pass into the combustion chamber of the cylinder for a period while the exhaust ports are closed. The inlet ports 14 are then closed and a period of compression of the air or mixture above both pistons follows. When the pistons are close to their uppermost positions the explosion or combustion of the combustible mixture takes place in the combustion chamber and both pistons again start downwardly on their working strokes.

The operation of the engine is best shown by the diagram illustrated in Fig. 2 representing the movement of both pistons during one complete revolution of crank shaft 6. The travel of pistons 8 and 9 from their upper dead center positions and back again

to the same positions is indicated by the lines 36 and 37 respectively. In deriving these lines, the stroke circle of the crank pin 7 is represented by either of the two circles 32¹, 32², indicated in dotted lines. The pitch circle of spur gear 30 is indicated by either of the dotted circles 33¹, 33², while the pitch circle of internal gear 31 is indicated by either of the dotted line circles 34¹, 34². The positions of bushing portion 29¹ of bushing 29 in twelve equidistant positions of the stroke circle of crank 7 are indicated by the small circles 35¹ located about circle 32¹ at the right of the diagram. Similarly the positions of bushing portion 29² at the same twelve points in the stroke circle of crank 7 are indicated by the small circles 35² positioned about stroke circle 32² at the left of the diagram.

It will be noted that the centers of pitch circles 33¹ and 33² are taken at the center of crank shaft 7 in the upper dead center position of the latter. The centers of pitch circles 34¹ and 34² are taken at the axis of crank shaft 6. The diameter of either pitch circle 33¹ or 33² is equal to the diameter of the stroke circle 32¹ or 32². It will be readily understood from this that spur gear 30 will engage continuously with internal gear 31 at all positions of the crank pin and that the spur gear will make two revolutions about the crank pin during each revolution of the latter.

The bushing portions 29¹ and 29², integral with or secured to the spur gear, will also make two revolutions about the crank pin during each revolution of the latter. The centers of bushing portion 29¹ for twelve equidistant crank positions are indicated by the points 1¹, 2¹, 3¹, etc., on the circumferences of the small circles 35¹. Similarly the centers of bushing portion 29² at twelve equally spaced crank positions are indicated by the points 1², 2², 3², etc., on the circumferences of the small circles 35² at the left of the diagram.

It will be evident that the rotation of the eccentric bushing portions 29¹ and 29² around the crank pin will affect the angular positions of the two connecting rods, the lower ends of which surround the said portions of the bushing. Each connecting rod may be considered, in effect, as connecting the center of one of the bushing portions with the corresponding piston, and the center of the bushing portion referred to will be moving inwardly of the stroke circle of the crank pin at certain positions of the bushing, and outwardly of the stroke circle of the crank pin at other positions, that is towards or away from the crank shaft center in the one case, or in the other.

The lines 36 and 37 indicating the travel of pistons 8 and 9 are laid out from the data referred to. Because of the fact that

the bushing portions 29¹ and 29² are so mounted that the eccentricity of portion 29¹, at the upper dead center position of the crank pin, is advanced in relation to the eccentricity of portion 29², the piston 8 which is connected to the advanced bushed portion 29¹ will obtain a lead over the piston 9 which is connected to bushing portion 29². Because of this arrangement the piston 8 will open the exhaust ports before piston 9 opens the inlet ports, piston 8 also closing the exhaust ports before piston 9 closes the inlet ports.

Line 36 starts from point 1A¹ and line 37 starts from point 1A² as pistons 8 and 9 start outwardly on their working strokes, as crank 7 starts downwardly from its upper dead center position. Lines 36 and 37 each have twelve positions indicated thereon, 1A¹ to 12A¹ and 1A² to 12A² respectively, corresponding to the twelve positions of the stroke circles 32¹ and 32². The charge having been fired at about the upper dead center position of crank 7, the gases will expand and do useful work on the two pistons, the inlet and exhaust openings being closed. Exhaust openings 13 will begin to open as the upper edge of piston 8 passes downwardly past the same, this occurring after about, say, 120° of the stroke cycle of the crank. As is shown on the diagram, the exhaust ports may begin to open at point 5A¹ on line 36. At the same point in the stroke circle of the crank, indicated by point 5A² on line 37, the inlet ports 14 have not begun to open.

The inlet ports begin to open shortly thereafter, this opening occurring at a point indicated as 5A^x on line 37, this point being indicated as intermediate positions 5A² and 6A² on line 37. A scavenging action accordingly begins at the point in the downward movement of the pistons indicated by point 5A^x, the mixture or fresh air admitted through the inlet ports 14 sweeping through the cylinder and driving the burned gases out through the exhaust ports 13 in the portion 3 of the duplex cylinder. This scavenging action continues until the exhaust ports are again closed by piston 8, this occurring at point 8A^x on line 36, which point is intermediate positions 8A¹ and 9A¹ on line 36.

The inlet ports are still open, as is indicated by the diagram, when the exhaust ports close, the inlet ports closing at position 9A² on line 37. The combustion chamber of the cylinder will be super-charged with mixture or fresh air admitted therein from pre-compression chamber 27 during the interval between the closing of the exhaust at point 8A^x and the closing of the inlet ports at point 9A².

Compression of the intaken mixture or fresh air in the combustion chamber will be

accomplished by both pistons during the interval represented by the portion of line 37 between points $9A^2$ and $1A^2$ at the bottom of the diagram and between points $9A^1$ and $1A^1$, at the bottom of the diagram, on line 36.

It will be understood that crank 7, referring to the two stroke circle diagrams, descends from position 1 to position 7 and again ascends from position 7 to position 1. Pistons 8 and 9, if their movements were not modified by rotation of the eccentric bushing, would accordingly make their down strokes from positions $1A^1$ and $1A^2$ to positions $7A^1$ and $7A^2$ on lines 36 and 37 respectively, and make their succeeding up strokes from these positions to points $1A^1$ and $1A^2$ at the lower ends of lines 36 and 37. The lowest positions of the pistons actually occur at points on lines 36 and 37 different from $7A^1$ and $7A^2$, as will be explained later.

It will also be noted that the working strokes of the two pistons continue from the beginning of the down strokes until point $5A^1$ is reached, that the exhaust stroke continues from point $5A^1$ until the closing of the exhaust ports at point $8A^x$; that the scavenging stroke continues from the opening of the inlet ports at points $5A^x$ to the closing of the exhaust ports at point $8A^x$; that the super-charge takes place between points $8A^x$ and $9A^2$ and that compression takes place between points $9A^1$ and $1A^1$.

It will also be understood that vertical distances on the diagram represent time intervals, and horizontal distances from the vertical lines $1A^1-1A^1$ and $1A^2-1A^2$ represent distances of the pistons away from their uppermost positions. Accordingly the speed of each piston at any point is indicated by the rate, at such point, at which its travel line 36 or 37 is diverging from the vertical line $1A^1-1A^1$, or $1A^2-1A^2$, connecting the beginning and end of such travel line. For example, piston 9 is travelling downwardly at approximately a constant speed from position $2A^2$ to $4A^2$ on line 37. The speed of piston 9 then decreases somewhat between positions $4A^2$ and $5A^2$ and decreases somewhat more between points $5A^2$ and $5A^x$. From point $5A^x$ to $7A^2$ piston 9 moves downwardly with a further decrease in speed and from point $7A^2$ to $8A^2$ it moves further downwardly at about the same speed. Between points $8A^2$ and $9A^2$ it begins to move upwardly again, at a greater speed than that with which it was descending just before that time. It will be noted that the piston moves down somewhat after the crank passes its lower dead center at 7, because the center of bushing portion 29^2 is on the inside of circle 32^2 and is moving outwardly, between positions 7^2 and 8^2 on circle 32^2 .

It will also be noted that piston 8 reaches its lowest position at about point $6A^1$ on line 36, before the crank has reached its lower dead center, because the center of bushing portion 29^1 is on the outside of circle 32^1 , and is moving inwardly, when position 6¹ is reached.

By comparing the various positions on lines 36 and 37 it will be noted that each connecting rod descends with a variable speed different from that of the other connecting rod and also ascends with a variable speed different from that of the other connecting rod, at various points in the stroke circle of the crank. It will be noted, for example, that at point $2A^2$ connecting rod 9 is moving downwardly more rapidly than is connecting rod 8 at its corresponding point $2A^1$, and has traveled further, as is evidenced by the fact that point $2A^2$ is further away from line $1A^2-1A^2$, than is point $2A^1$ from line $1A^1-1A^1$. The rates of travel and distances traveled by the two pistons at the various points in the stroke circle of the crank will, of course, be caused by the arrangement and rotation of the bushing portions 29^1 and 29^2 , as described.

Pistons 8 and 9 will open ports 26 and 26¹ to admit mixture or fresh air into pre-compression space 27, as stated, when both pistons are approaching their upper dead center positions. Piston 8 starts to open these ports 26 at approximately position $12A^1$ on line 36 of the diagram, Fig. 2, and again closes them at approximately point $2A^x$ on line 36, that is shortly after piston 8 has left its upper dead center position on its following down stroke. Piston 9 starts to open inlet ports 26¹ at approximately position point $12A^x$ on line 37 and again closes the same at about position $2A^2$ on line 37 on the next down stroke of piston 9. The air or mixture drawn into chamber 27 through ports 26 and 26¹ will be compressed in chamber 27, after the closing of these ports, during the down strokes of both pistons. When point $5A^x$ on line 37 of the diagram has been reached, during the down strokes of the pistons, the inlet ports 14 begin to open as stated, whereupon the compressed air or mixture in chamber 27 will rush therefrom into the combustion chamber above the pistons until the inlet ports 14 again close at substantially position $9A^2$, as stated.

It will be noted that ports 26 and 26¹ respectively open at slightly different times (points $12A^1$ and $12A^x$) and close at slightly different times (points $2A^x$ and $2A^2$).

In the diagram Fig. 2, the distance between the dotted construction lines 38, 38¹, represents the width of inlet ports 14, while the distance between the dotted construction lines 39, 39¹, represents the width of the

exhaust ports 13. Accordingly the cross hatched area 40 included between line 38¹ and the portion of the travel line 37 of piston 9 which extends beyond the same represents the period during which the inlet ports are open. Also, area 41 between line 39¹ and the portion of travel line 36 which extends beyond the same represents the period during which the exhaust ports are open.

From observation of areas 40 and 41 it will be evident that the inlet ports do not open fully until approximately point 8A² has been reached, which point is a substantial distance more than half way from point 5A¹ to point 9A². Therefore, the inlet ports will not open fully until more than half of the period during which these ports are at least partly open has elapsed. It will also be noted that the exhaust ports are fully opened at or before position 6A¹ on line 36 has been reached, which point is less than half of the distance from point 5A¹ to point 8A², so that the exhaust ports will be fully open before half of the period during which they are at least partly open has elapsed. The exhaust ports are fully opened at approximately the moment the inlet ports begin to open.

The quick full opening of the exhaust ports permits a quicker exhaust of the burnt gases, than heretofore. The fact that the inlet ports open only slightly at first permits scavenging of the burnt gases from the cylinder by the aid of fresh charge of less volume than is usual so that there is less likelihood of some of the fresh charge escaping through the exhaust ports with the burnt gases. A more efficient vacuum in the cylinder than is usual will be produced during the period that the exhaust ports are open before the inlet ports begin to open, because of the greater velocity achieved by the burnt gases in escaping from the exhaust ports during the early portion of the opening of the exhaust ports, such greater velocity being due to the greater area of exhaust port opening at this time.

The greatest width of opening of the inlet ports, it will be noted, occurs only at about point 8A² on line 37 at which time the exhaust ports are nearly closed. Hence the scavenging of the burnt gases from the cylinder will be substantially completed before the inlet ports are fully open.

A modified construction is illustrated in Figures 7 to 10 inclusive. As is here shown, in place of having a duplex cylinder with parallel portions side by side as in the construction previously described, a duplex cylinder may be employed, the two working portions of which are arranged in a straight line with a common axis.

Referring to Fig. 7, a casting 42 is illustrated containing a cylinder with pistons 8¹ and 9¹ mounted in the opposite ends

thereof. Piston 8¹ is connected by connecting rod 10¹ to a crank 7^a on crank shaft 6^a rotatably mounted in crank case 2^a in one end of the construction. Piston 9¹ is connected by connecting rod 11¹ to crank 7^b of crank shaft 6^b rotatably mounted in crank case 2^b at the other end of the construction. The pistons move towards and away from each other, a combustion chamber 5^a being established between the same. A spark plug or spark plugs may be used for igniting the mixture in this combustion chamber, or fuel injectors may, of course, be used when fresh air is compressed in the combustion chamber as in the first form of construction described. An opening is indicated at 23^a for a spark plug or fuel injector.

Crank shaft 6^a may be connected suitably as by beveled gears 43, 44, to a shaft 45 extending parallel to the cylinder and crank shaft 6^b may be connected to shaft 45 by similar connections such as the beveled gears 46, 47. By such means or other suitable means the two pistons will be caused to move in properly timed relation to each other. Shaft 45 may be the main driven shaft.

The construction here illustrated will in other respects be similar to the form of construction previously described. An eccentric bushing 29^b is mounted on crank pin 7^a and an eccentric bushing 29^c on crank pin 7^b. These bushings are similar to bushing portions 29¹ and 29² respectively shown in Figures 1, 5 and 6, and one of the same, namely bushing 29^b, will have its axis arranged at an angular advance with respect to the axis of bushing 29^c in the same manner that the eccentricity of bushing portion 29¹ is arranged in advance of bushing portion 29² in Figs. 5 and 6. In Fig. 7 the two cranks are shown at their inner dead center positions, at which time the explosion of the compressed charge in the combustion chamber is to take place to start the two pistons outwardly on their working strokes. At this time bushing 29^b is in the same position as the position of bushing portion 29¹ shown in Fig. 5 while bushing 29^c may be in the same position as that shown for bushing portion 29² in Fig. 6.

Bushing 29^b is illustrated as having a spur gear 30^a integral therewith or secured thereto, concentric with crank 7^a, and adapted to continuously mesh with an internal gear 31^a secured within crank case 2^a. Similarly bushing 29^c is provided with a spur gear 30^b which continuously meshes with an internal gear 31^b. Gears 30^a and 30^b may be similar to gear 30 and internal gears 31^a and 31^b may be similar to internal gear 31, previously described, and the proportion and arrangement of the parts may be the same as in the case first described.

Piston 8¹, entirely similar to piston 8, previously described, will control the exhaust

ports 13^b which extend through the inner wall 3^a of the cylinder casting, as shown in Figures 7 and 8. The annular space 13^c into which exhaust ports 13^b open communicates 5 with the outside air or exhaust muffler through opening 13^d.

Piston 8¹ also controls the intake ports 26^a for the precompression chamber 27^a; (see Figs. 7 and 9). Precompression inlet ports 10 26^a extend about the periphery of the inner wall 3^a of the cylinder, and extend into an annular space 28^a which communicates with the open air through opening 28^b. The inner cylindrical portion 15^a of piston 8¹ is 15 adapted to slide within the tubular flange 20^a of member 18^a, while portion 15^b of piston 9¹ slides within tubular flange 20^b of member 18^b. The annular space 28^a, as 20 shown in Figs. 7 and 9, is formed within an outward extension of inner wall 3^a of the casting, adjacent to the water jacket space 24^a.

The inlet ports 14^a are controlled by piston 9¹, (see Figs. 7 and 10), in the same manner 25 as inlet ports 14 are controlled by piston 9 in Fig. 1. A passage 43 is formed in the casting, as is shown in Figs. 7, 8 and 9, between the outer wall of the casting and the water jacket space 24^a, and also outside of 30 the annular space 28^a through the inner walls of which the precompression intake ports 26^a extend. This passage 43 connects the precompression chamber 27^a adjacent to piston 8¹ to the similar precompression space 27^b at the other end of the duplex cylinder 35 adjacent to piston 9¹.

From the above it will be obvious that the construction illustrated in Figs. 7 to 10 inclusive operates in the same general manner 40 as the construction illustrated in Figs. 1 to 6, a pair of crank shafts being substituted for the single crank shaft utilized in the first form of the invention described. The operation of the engine shown in Fig. 7 may be 45 illustrated by the diagram Fig. 2, in the same manner as has previously been described.

The invention includes engines each having a single duplex cylinder such as the 50 forms of cylinder shown in Figs. 1 and 7, and also includes engines each having a plurality of cylinders arranged in various combinations. One such arrangement is indicated diagrammatically in Fig. 11 in 55 which a pair of duplex cylinders 100, 101, are mounted side by side. Each of the cylinders comprises a pair of cylinder portions 103, 104, and 103¹, 104¹, which are arranged in the same manner as the cylinders 3 and 4 60 of the construction shown in Figs. 1 to 6 of the drawings. A single crank shaft 106 is indicated having a pair of cranks 107 and 107¹, which may be 180° apart. Eccentric bushings are mounted on the cranks 107, 65 107¹, each of which is similar to the bushing

29 (Fig. 1). These bushings are rotated about the cranks in the same manner as has been previously described. The bushing arranged on crank 107 has a pair of portions 70 similar to bushing portions 29¹ and 29² previously described which are connected by connecting rods to the pistons in cylinder portions 103 and 104. The construction is the same in the case of the other cylinder 75 104. It is obvious that this arrangement may be modified as for example to provide three cylinders similar to 104 in which case the three throws of the crank shaft shaft would be separated 120° apart.

In the arrangement shown in Fig. 12 a 80 plurality of duplex cylinders of the form illustrated in Figs. 7 to 10 are mounted side by side. These cylinders are indicated at 203, 203^a, 203^b and 203^c. A pair of crank shafts are indicated at 206^a, 206^b, extending opposite the respective ends of the cylinders. These crank shafts are connected together so as to operate in synchronism, by means of a shaft 245 parallel to the axes of 85 the cylinders and connected to the two crank shafts by suitable means such as the beveled gears 244, 243, indicated at the ends of shaft 245. The axes of all the cylinders will lie in the same plane with the axes of the two crank shafts. Each crank shaft such as 90 206^a will have a plurality of cranks thereon, one for each of the cylinders, such for example, as the crank indicated at 207^a, each of which cranks will have an eccentric bushing thereon rotated about the crank in the 95 manner which has already been described. Each of the cylinders will have a pair of axially aligned pistons therein which may be similar to pistons 8¹ and 9¹, shown in Fig. 7, connected by connecting rods to the eccentric bushings on the cranks. The cranks may be arranged at suitable angular intervals upon the crank shafts in accordance 100 with the number of parallel cylinders used, in the well known manner.

Another arrangement is indicated in Fig. 13, in which a plurality of cylinders 303, 303^a, 303^b, etc., are arranged in circular alignment about a shaft which may be the 115 main driven shaft indicated at 345, the axis of which is parallel to the axes of the cylinders. The various cylinders may be of either the form shown in Fig. 1, or the form shown in Fig. 7, the form of cylinder shown in Fig. 7 being indicated in the arrangement illustrated in Fig. 13. Each of the cylinders 303, etc., has a pair of axially aligned pistons therein each of which is connected by a connecting rod to an eccentric bushing 120 on a crank shaft extending across the adjacent end of the cylinder. A separate crank shaft having a single throw or crank will be provided for each piston. One such crank shaft is indicated at 306^a which as indicated 125 may be suitably connected as by beveled 130

gears to the driven shaft 345, the arrangement being the same in the case of all the cylinders. Each crank shaft will extend radially with respect to the driven shaft 345, the axis of each crank shaft extending at right angles to the axis of the driven shaft and each of the crank shafts at one end of the construction being provided with beveled gears such as the gear 343, all of these gears meshing with a single gear 344 on the adjacent end of shaft 345.

It should be understood that various modifications of the structures described may be made without departing from the spirit of the invention, and also that various features of the constructions described may be used so far as concerns certain aspects of the invention, without certain other features.

It will be noted that the expression "crank shaft means" in certain of the claims is intended to include a single crank shaft such as that shown in Fig. 1 or a plurality of crank shafts such as are illustrated in Fig. 7, and that the expression "crank means of said crank shaft means" similarly refers to a single crank or a plurality of cranks on said crank shaft or crank shafts. Similarly the expression "bushing means on said crank means" refers to a bushing on a single crank such as crank 7 in Fig. 1, or a plurality of bushings such as bushings 29^a and 29^c on cranks 7^a and 7^c in Fig. 7. The statement that such crank means are "positioned at the same points of the crank stroke circle" should be taken to include the case of a single crank such as the crank 7 in Fig. 1, both end portions of which are in the same angular position with respect to the stroke circle of the crank shaft; or a plurality of cranks, such as cranks 7^a and 7^b of Fig. 7, which are positioned in the same angular relation to the stroke circles of their respective crank shafts. Likewise the reference in certain claims to a cylinder having a pair of cylinder portions the axes of which portions are arranged in the same plane, includes a cylinder such as that shown in Fig. 7 having two working portions, the axis of one of which is in alignment with the axis of the other, as well as a construction such as that shown in Fig. 1 in which the two cylinder portions are side by side.

It will be noted that all novel combinations which may be common to this application and to my co-pending application Serial No. 558,102, internal combustion engines, filed May 3, 1922, are sought to be claimed herein.

It should be understood that while I have described certain forms and features of the invention with particularity, the invention is not limited to the exact details which have been described, but that various modifications may be employed, as will be clear to those skilled in the art, after reading this specifica-

tion, the scope of the invention being indicated by the accompanying claims.

What I claim is:

1. In an internal combustion engine, the combination of a crank shaft, a cylinder comprising a pair of parallel cylinder portions arranged with their axes in a plane which also includes the axis of the crank shaft, pistons in said cylinder portions, and connections between said pistons and crank shaft such that both pistons will have strokes of equal length, and both will start together on certain strokes in the same direction, from corresponding points in their respective cylinder portions at approximately the same times, but that one piston will obtain a lead over the other after passing such point.

2. In an internal combustion engine, the combination of a duplex cylinder having a pair of cylinder portions and a common combustion chamber, pistons in said cylinder portions, and crank shaft means, the axes of said cylinder portions and crank shaft means all being arranged in the same plane, and connections between said pistons and crank shaft means, such that both pistons will have strokes of equal length, and will pass certain corresponding points of their respective cylinder portions while moving in the same direction at approximately the same time, but that one piston will obtain a lead over the other after passing such point.

3. In an internal combustion engine, the combination of a duplex cylinder having a pair of cylinder portions and a common combustion chamber, pistons in said cylinder portions, and crank shaft means, the axes of said cylinder portions and crank shaft means all being arranged in the same plane, and connections between said pistons and crank shaft means, including connecting rods and means interposed between said connecting rods and the crank means of said crank shaft means, said interposed means being movable relatively to said crank means and arranged to cause one of said pistons to obtain a lead over the other during strokes thereof.

4. In an internal combustion engine, the combination of a duplex cylinder having a pair of cylinder portions and a common combustion chamber, pistons in said cylinder portions, and crank shaft means, the axes of said cylinder portions and crank shaft means all being arranged in the same plane, said crank shaft means having crank means thereon positioned at the same points of the crank stroke circle, and connections between said pistons and crank means including connecting rods of equal length, arranged to cause one of said pistons to obtain a lead over the other during strokes thereof, said pistons being arranged to start together on their working strokes.

5. In an internal combustion engine, the combination of crankshaft means having

crank means thereon positioned at the same points of the crank stroke circle, eccentric bushing means mounted on said crank means, means for rotating said bushing means about said crank means, a pair of cylinder portions, pistons therein, and connecting rods connecting said pistons and eccentric bushing means, said cylinder portions having exhaust and intake ports respectively, controlled by said pistons.

6. In an internal combustion engine, the combination of a crankshaft having a crank pin, a pair of eccentrics on said crank pin, one of the same being angularly advanced with respect to the other, a pair of cylinder portions, pistons therein, connecting rods connecting said pistons and eccentrics, respectively, and positive means for rotating said eccentrics together about said crank pin during the rotation of said crank pin about the axis of said crankshaft.

7. In an internal combustion engine, the combination of a crankshaft having a crank pin, a pair of eccentrics on said crank pin, one of the same being angularly advanced with respect to the other, a cylinder structure comprising a pair of cylinder portions and a common combustion chamber, one of said portions having an inlet port and the other an exhaust port, pistons in said cylinder portions, controlling said ports respectively, connecting rods connecting said pistons and eccentrics respectively, and means for rotating said eccentrics together about said crank pin during the rotation of the latter to cause the exhaust port to be opened and closed before the inlet port is opened and closed.

8. In an internal combustion engine, the combination of crankshaft means having crank means thereon positioned at the same points of the crank stroke circle, eccentric means on said crank means having two portions, one of the same being angularly advanced with respect to the other, a pair of cylinder portions, pistons therein, connecting rods connecting said pistons and said eccentric means portions, respectively, and positive means for rotating said eccentric means about said crank means during the rotation of said crank means.

9. In an internal combustion engine, the combination of a cylinder structure comprising a pair of cylinder portions, one of the same having an inlet port and the other an exhaust port, pistons in said cylinder portions, controlling said ports, respectively, crank shaft means having crank means thereon at the same points of the crank stroke circle, eccentric means on said crank means, connecting rods connecting said pistons and eccentric means, and means for rotating said eccentric means about said crank means in such manner as to cause the exhaust port to be uncovered by one of said

pistons before the inlet port is uncovered by the other piston, and to cause the exhaust port to be closed by the first named piston before the inlet port is closed by the second named piston.

10. In an internal combustion engine, the combination of a duplex cylinder having a pair of cylinder portions and a common combustion chamber, one of said portions having an inlet port and the other an exhaust port, pistons in said cylinder portions, controlling said ports, respectively, crankshaft means, and connections between said pistons and crankshaft means, including eccentric means, such that said pistons move with variable speeds, that of one being different from that of the other, both pistons have a common working stroke, and one piston will obtain a lead over the other at appropriate times to open and cover the exhaust port before the other piston opens and covers, respectively, the inlet port.

11. In an internal combustion engine, the combination of a cylinder having an inlet port, a piston in said cylinder controlling the opening and closing of said port, a crank shaft having a crank, an eccentric member on said crank, a connecting rod connecting said piston and eccentric member, and means for rotating said eccentric member about said crank in such a manner that the port will be gradually opened for a period until it is fully open, and will then be fully closed within a shorter period.

12. In an internal combustion engine, the combination of a cylinder having an inlet port, a piston in said cylinder controlling the opening and closing of said port, a crank shaft, connections between said piston and crank shaft including an eccentric, and means for rotating said eccentric in such a manner that the port will be gradually opened for a period until it is fully open, and will then be fully closed within a shorter period.

13. In an internal combustion engine, the combination of a cylinder having an exhaust port, a piston in said cylinder controlling the opening and closing of said port, a crank shaft having a crank, an eccentric member on said crank, a connecting rod connecting said piston and eccentric member, and means for rotating said eccentric member about said crank in such a manner that the port will be fully opened within a certain period, and will then be gradually closed during a longer period.

14. In an internal combustion engine, the combination of a cylinder having an exhaust port, a piston in said cylinder controlling the opening and closing of said port, a crank shaft, connections between said piston and crank shaft including an eccentric, and means for rotating said eccentric in such a manner that the port will be fully opened

within a certain period, and will then be gradually closed during a longer period.

15. In an internal combustion engine, the combination of cylinder means having inlet and exhaust ports, and means including sliding means and operating means of variable speed therefor for opening and closing said ports periodically in such manner that the exhaust port will be substantially fully open at the time when the inlet port begins to open, and that the exhaust port will gradually close thereafter during the time that the inlet port gradually opens. 70

16. In an internal combustion engine, the combination of cylinder means having inlet and exhaust ports, and means, including sliding means and operating means therefor of variable speed for opening and closing said ports periodically in such manner that the exhaust port will begin to open before the inlet port, and will close before the inlet port, and that the inlet port will open gradually, so that its full opening will not take place until the exhaust port is nearly closed. 75

17. In an internal combustion engine, the combination of cylinder means having inlet and exhaust ports, and means, including sliding means and operating means therefor of variable speed for opening and closing said ports periodically in such manner that the exhaust port will begin to open before the inlet port, and will close before the inlet port, and that the full opening of the inlet port will be retarded, and its closing accelerated, and the full opening of the exhaust port will be accelerated, and its closing retarded. 80

18. In an internal combustion engine, the combination of cylinder means having inlet and exhaust ports, a pair of pistons in said cylinder means, one controlling the opening and closing of the inlet and the other controlling the opening and closing of the exhaust port, and means including eccentrics for reciprocating said pistons in such a manner that the exhaust port will be substantially fully open at the time when the inlet port begins to open, and that the exhaust port will gradually close thereafter while the inlet port gradually opens. 85

19. In an internal combustion engine, the combination of cylinder means having inlet and exhaust ports, and means including reciprocating members and eccentrics connected therewith for opening and closing said ports periodically in such manner that the exhaust port will be substantially fully open at the time when the inlet port begins to open, and that the inlet port will open gradually while the exhaust port closes gradually, the maximum opening of the inlet port occurring at about the time the exhaust port is fully closed. 90

20. In an internal combustion engine, the combination of a cylinder structure comprising a pair of cylinder portions, one of the same having an inlet port and the other an exhaust port, pistons in said cylinder portions, controlling said ports respectively, crankshaft means, and connections between the same and said pistons, including eccentric means, and means for rotating said eccentric means, in such manner that the exhaust port will be quickly opened and gradually closed, and the inlet port will be gradually opened and quickly closed. 95

21. In an internal combustion engine, the combination of a cylinder structure comprising a pair of cylinder portions, one of the same having an inlet port and the other an exhaust port, pistons in said cylinder portions, controlling said ports respectively, crankshaft means, and connections between the same and said pistons; including eccentric means, and means for rotating said eccentric means, in such manner that the exhaust port will be substantially fully open at the time when the inlet port begins to open, and that the inlet port will open gradually while the exhaust port closes gradually, the maximum opening of the inlet port occurring at about the time the exhaust port is fully closed. 100

22. In an internal combustion engine, the combination of a cylinder, a piston therein, and means including an eccentric for reciprocating said piston in such manner that all of its strokes in one direction will occupy a longer time interval than its strokes in the opposite direction, while all the strokes of said piston will be equal in length. 105

23. In an internal combustion engine, the combination of a cylinder having a port, a piston in said cylinder controlling the opening and closing of said port, and means including an eccentric for reciprocating said piston in such a manner that the port will be uncovered thereby during one period of time until it is fully open and will then be closed thereby during a period of time of different length. 110

24. In an internal combustion engine, the combination of cylinder means having a common combustion chamber, a pair of pistons in said cylinder means, and means including eccentrics for reciprocating said pistons in such manner that both will have strokes of equal length, but that all of the inward strokes of one of the same will occupy longer time intervals than its outward strokes, while all of the inward strokes of the other will occupy shorter time intervals than its outward strokes. 115

25. In an internal combustion engine, the combination of cylinder means having a common combustion chamber, a pair of pistons in said cylinder means, said cylinder means having exhaust and inlet ports controlled respectively by said pistons, and 120

- means including eccentrics for reciprocating said pistons in such manner that, during the working stroke of both, the travel of the piston controlling the exhaust port will be accelerated and the travel of the piston controlling the inlet port will be retarded, to cause the opening of the exhaust port before that of the inlet port, both pistons having all strokes of equal length.
26. In an internal combustion engine, the combination of cylinder means having a common combustion chamber, a pair of pistons in said cylinder means, said cylinder means having exhaust and inlet ports controlled respectively by said pistons, and means including eccentrics for reciprocating said pistons in such manner that, during the outward and inward strokes of both, the exhaust port will be fully opened at about the moment that the inlet port begins to open, and that the exhaust port will be gradually closed while the inlet port is gradually opened, and that the inlet port will then be fully closed shortly after the exhaust port has been closed.
27. In an internal combustion engine, the combination of cylinder means having inlet and exhaust ports and means for opening and closing said ports periodically, said means comprising a pair of reciprocating members, rotating means, and connections between said rotating means and said members such that the exhaust port will be quickly opened by one of said members and will be gradually closed thereafter, and that the other of said members will begin to open the inlet port when the exhaust port is substantially fully open, and will open the inlet port gradually during the time that the exhaust port is being gradually closed.
28. In an internal combustion engine, the combination of a cylinder, having a port opening therein, a piston in said cylinder, a crankshaft and means for reciprocating said piston with an accelerated inward stroke and a retarded outward stroke, comprising an eccentric bushing on the crank pin of said crankshaft, means for rotating said bushing about said crank pin during the rotation of the crankshaft, and a connecting rod connected with said piston and journalled on said bushing, all of said parts being so arranged as to cause said piston to uncover said port towards the end of all of its outward strokes, and then again cover the same.
29. In testimony whereof I have signed my name to this specification, at New York city, N. Y., this 20th day of April, 1922.

CHARLES J. TÓTH.
